UNITED STATES PATENT OFFICE.

EMIL JOSSE AND WILHELM GENSECKE, OF CHARLOTTENBURG, GERMANY, ASSIGNEES
TO GESELLSCHAFT FUER KÄLTEINDUSTRIE MIT BESCHRÄNKTER HAFTUNG, OF
BERLIN, GERMANY, A CORPORATION OF GERMANY.

INJECTOR.

1,119,515.

Specification of Letters Patent.

Patented Dec. 1, 1914.

Application filed October 31, 1912. Serial No. 728,760.

To all whom it may concern:

Be it known that we, EMIL JOSSE and WILHELM GENSECKE, citizens of the Empire of Germany, residing at Charlottenburg, Germany, have invented certain new and useful Improvements in Injectors, of which the following is a specification.

This invention relates to improvements in steam jet apparatus and has for its object to increase the efficiency of the said steam jet apparatus. This object is attained in accordance with the present invention by increasing the contact surface between the driving and driven media without the conversion of energy in the nozzle being interfered with. To this end, the enlargement of the cross sectional area both of the nozzle and of the diffuser takes place in each case mainly in one plane and the planes of the cross sectional expansion of the nozzle and diffuser are at right angles to one another.

The invention is illustrated in various embodiments in the accompanying drawings, in which—

25 Figure 1 shows a longitudinal section of a nozzle and a diffuser of rectangular slot form in cross section; Fig. 2 shows the same in longitudinal section at right angles to Fig. 1; Fig. 3 is a cross section on the line 30 1—2 of Fig. 1; and Fig. 4 a plan of another form of the nozzle viz. cross shaped in cross section.

In the first form (in which the nozzle and diffuser are expanded in two planes at right angles to one another) the cross sectional form of the nozzle and diffuser may be that of a rectangular slot or of a cross or star. Owing to the small thickness of the jet, differences of velocity between the core and the edge cannot occur. In addition, as the diffuser is of the breadth of the nozzle at the outlet and as the necessary alterations of the cross section take place in a plane at right angles to the breadth of the nozzle the further advantage is obtained that the stream lines experience such slight difference in direction that disturbances by separation from the walls and by stoppage are avoided. The expansion of the nozzle α as shown in Figs. 1 and 2 takes place in one plane while the distance between the nozzle walls is constant in the plane at right angles

thereto. Thus the nozzle is widened from the inlet to the outlet to form a rectangular extended slot. The diffuser b is arranged in a different manner. The distance apart of the diffuser walls is constant in that plane in which the nozzle is expanded while the tapering and expansion of the diffuser take place in the plane at right angles thereto in which the distance between the walls of the nozzle is constant (Fig. 2). As a result the forcing jet enters the diffuser b as a narrow uniformly flowing band and a large contact surface between the driving medium and the medium to be driven is formed while the differences of velocity in the driving stream cannot occur as all parts of the liquid strike the particles to be driven. At the same time the arrangement in the diffuser produces only small alterations in direction of the stream lines. The result of this arrangement is a considerable increase in the efficiency of the jet pump.

The embodiment illustrated in Fig. 4 differs from that shown in Figs. 1 to 3 only in this that the nozzle α is of cross or star shape in cross section. It has also the particular feature that the expansion of the nozzle and of the diffuser takes place in planes at right angles to one another.

What we claim as new and desire to secure by Letters Patent of the United States is:

1. The combination of a nozzle of rectangular cross-section with a diffuser of rectangular cross-section, said nozzle and diffuser being enlarged in planes at right angles to each other.

2. The combination of a plurality of nozzles of rectangular cross-section intersecting each other with a plurality of diffusers of rectangular cross-section intersecting each other, each nozzle and diffuser being enlarged in planes at right angles to each other.

In testimony whereof we affix our signatures in presence of two witnesses.

EMIL JOSSE.
WILHELM GENSECKE.
